UNITED STATES PATENT OFFICE.

WILLIAM E. NIECE, OF SANDY LAKE, PENNSYLVANIA.

DISH-WASHING APPARATUS.

No. 820,594.

Specification of Letters Patent.

Patented May 15, 1906.

Application filed May 4, 1905. Serial No. 268,764.

To all whom it may concern:

Be it known that I, WILLIAM E. NIECE, a citizen of the United States, residing at Sandy Lake, in the county of Mercer and State of Pennsylvania, have invented certain new and useful Improvements in Dish-Washing Apparatus, of which the following is a specification, reference being had therein to the accompanying drawings.

10 My invention refers to improvements in dish-washing apparatus, and has for its objects to provide a basket-support adapted to be transported along a supporting trolley bar or rod, said support comprising a casing containing a compression-spring with supporting trolley-wheels and a framework depending from the spring adapted to carry the dish-containing basket, together with a securing-latch and other features of detail, as 15 shall be more fully hereinafter described.

The apparatus is designed to support a basket adapted to contain a considerable number of dishes and to be used in combination with one or more washing chambers or 20 tanks, preferably two, for washing and rinsing, into which the basket is lowered and reciprocated up and down by the operator while depending from the supporting-spring. The principal function of the spring is to facilitate the up-and-down washing operation, 25 thereby rendering it merely necessary to apply sufficient downward pressure upon the basket to immerse the contents in the water of the tank, the spring acting to raise it and to facilitate the operation, while greatly reducing the labor of the attendant.

Figure 1 is a view in side elevation of my improved dish-washing apparatus, showing the dish-holding basket in position for immersion over one of the chambers of the 30 washing-tank. Fig. 2 is an end elevation thereof, showing the basket immersed in the tank, said tank being in section. Fig. 3 is an enlarged vertical sectional view on the line III III of Fig. 1, showing the basket tipped in position for being filled. Fig. 4 is a similar section at right angles to Fig. 3, the basket being shown in its normal position. Fig. 5 is a cross-sectional detail view on the line V 35 V of Fig. 4. Fig. 6 is a vertical sectional view similar to Fig. 4, illustrating a modified construction wherein the supporting-rods are entirely inclosed within the spring-casing.

Referring now to the drawings, wherein 40 the invention is illustrated, 2 2 represent the compartments of a double tank which are

preferably provided with heaters 3 of any suitable kind and the usual supply-faucets and waste-pipes incident to apparatus of this character. While I have shown an arrangement of two tanks, it is obvious that a single one or three or more tanks may be employed, the advantage of a plurality of tanks being that the dishes may be washed in one water and subsequently washed in the other or 45 others of the series.

4 is the basket, composed of a suitable framework of wire or similar material having a surrounding body portion of wire-netting or suitable perforated material, the basket 50 being preferably rectangular in form and of a size adapted to freely enter the interior of the tank with sufficient surrounding clearance-space—say about one inch on each side—for circulation of the water. An advantage 55 of such construction is that the basket practically fills the interior of the tank, and as it is forced downwardly through the water the water will be caused to circulate upwardly through the interior of the basket and around 60 the contents, thoroughly washing them and removing any adhering matter. A further advantage is that any splashing or overflow 65 of the water is prevented, the basket acting as a plunger, practically confining the water 70 and forcing it to pass through the basket and around the contents, as stated.

For the purpose of resiliently supporting the basket I provide the framework consisting of supporting rods or bars 5 5, crossed at 75 6, as shown, thereby providing a convenient handhold for the operator and terminating in oppositely-directed arms 7 7, depending downwardly and provided with terminal hooks 8, upon which the bails 9 9 of the 80 basket are carried. The bars 5, preferably formed of an integral piece, are arranged downwardly along a spring-casing 10, having in its interior a compression coiled-spring 11, upon which the upper cross portion 12 of 85 supporting-rods 5 rests, a suitable vertical slot 13 being provided at each opposite side of the case, thereby permitting sufficient downward travel of the supporting-frame to entirely 90 immerse the basket. The rods 5 of the frame 100 are engaged by guides 14, extending outwardly on opposite sides of the casing.

The casing consists of a section of tubing or pipe and is provided at its bottom portion with a plug 15, upon which the spring 11 105 rests, as shown, while the upper portion is closed by a two-part bearing 16, said plug

and bearing being suitably secured in the lower and upper ends of the tube by any suitable means—as by screw-threads, screws, or rivets. For the purpose of supporting the 5 entire casing and framework I have provided the trolley-frame 17, which may conveniently be made of a single bar of metal, as shown, passing through the two-part bearing 16, having the oppositely-extending 10 arms deflected outwardly beyond the center, as shown at 18, and terminating in inwardly-turned horizontal gudgeons or studs 19, providing trolley-wheel bearings. The trolley-wheels are mounted on these bearings centrally 15 over the spring-case, as shown in Figs. 2 and 3, and are preferably concave or grooved, as shown, adapted to travel upon the trolley-bar 21, supported upon suitable brackets 22 from the wall or ceiling. The 20 trolley-bar 21 may conveniently be made of pipe, slotted at one side, so as to provide for the insertion at intervals of the supporting-brackets 22, thus providing a cheap convenient construction, and the supporting-wheels 20 are so located with relation to the 25 offset portion 18 of the frame and to the top of the two-part bearing 16 that there is just sufficient clearance for the longitudinal travel of the frame, while disengagement 30 from the trolley-bar will be effectually prevented at all points.

Depending downwardly from the lower portion of the spring-tube or from the plug 15 thereof is a spring-latch 23, having a hook 35 24, adapted to engage the basket-supporting portion of the frame, as the handle 6, so as to effectually hold it against vertical movement until the spring-latch is detached. This latch is provided with a downwardly-extending thumb-terminal 25, by which the operator may detach the same from engagement while holding the frame, or it may be detached by the other hand.

When being filled, the basket is preferably 45 tipped upwardly into the position shown in Fig. 3, in which position it may conveniently be held by a supporting-hook 26 at one side, or it may be set upon an inclined table or support for the same purpose. By this 50 means the basket may be always filled or emptied while supported upon the hooks, thus obviating the necessity of lifting or moving the basket by manual power. This is of great advantage and allows of the use of 55 the invention without the exertion of especial strength. In this position it may be more easily filled with dishes without danger of breakage or of subsequent shifting, and when filled is normally supported in the 60 horizontal position shown in Figs. 1 and 4, when it is ready for immersion.

In Fig. 6 I show a modified construction of the spring-supporting shell and basket-carrying frame wherein the rods 5' extend upwardly within the coiled spring 11', engaging

the spring at the top by nuts 27 on the ends of the rods or in any other suitable manner. In this construction a latch-holding bearing 28 is provided above the handle 6', thereby preventing interference with the hand. The 70 advantage of this construction is that the framework is entirely inclosed within the casing, the rods passing upwardly through the bottom portion, while the arrangement of the parts and their method of operation are 75 otherwise the same as has been described. It will be understood also that the basket-supporting frame may be secured to the lower end of an expansion-spring of any suitable construction. 80

The operation of the invention will be readily understood from the foregoing description. After having been filled with dishes at any convenient point the basket is carried by the trolley into a position above 85 one of the tanks 2, whereupon the latch-hook 24 is released and the operator then presses downwardly, forcing the basket and its contents through the water in the tank, as has been stated. The operation of pressing 90 down and lifting up by the spring is continued sufficiently long to thoroughly cleanse the dishes, the strength of the spring being such as to practically counterbalance the 95 weight of the basket and its contents, thus rendering the operation very comparatively easy, after which the same operation may be 100 repeated in one or more of the adjacent tanks, the surplus water allowed to drain off, when the washed dishes may be again carried along upon the trolley to any desired point and removed from the basket.

The advantages of my invention will be readily appreciated by all those familiar with the operation of washing dishes, particularly 105 in large numbers—as in restaurants, hotels, &c. It is very thorough in its action, the basket acting as a plunger and forcing the water with considerable pressure against the dishes at all sides, while no especial care is necessary 110 in placing the dishes in the basket, inasmuch as the regurgitation of the water in all directions insures the washing of every surface. It will be understood that the apparatus may be conveniently installed in suitable relation 115 with accompanying tables or other elements of culinary equipment, also that the device may be changed or varied by the skilled mechanician as to its details or various features of construction; but all such changes are to be 120 considered as within the scope of the following claims.

What I claim is—

1. The combination with a water-tank, of a perforated rectangular basket adapted to fit non-rotatably within the tank, and supporting means for the basket provided with a suspended spring shell or casing, a compression-spring supported thereby, and supporting devices for the basket depending from and sup- 130

- ported upon said spring, substantially as set forth.
2. The combination with a water-tank, of a perforated rectangular basket adapted to fit non-rotatably within the tank, and supporting means for the basket provided with a suspended spring shell or casing, a compression-spring supported thereby, and supporting devices for the basket depending from and supported upon said spring, with a wheeled carriage therefor, substantially as set forth.
3. The combination with a water-tank, of a perforated rectangular basket adapted to fit non-rotatably within the tank, and supporting means for the basket provided with a suspended spring shell or casing, a compression-spring supported thereby, and supporting devices for the basket depending from and supported upon said spring, provided with basket-carrying terminals, and a latch attached to said case, substantially as set forth.
4. A basket-support consisting of a casing provided with a compression-spring, a depending framework supported upon the spring having a basket-carrying terminal, and a latch attached to the casing, substantially as set forth.
5. A basket-support consisting of a casing provided with a compression-spring, a depending framework supported upon the spring having basket-carrying terminals, a supporting wheeled carriage therefor, and means adapted to support the basket directly from the casing, substantially as set forth.
6. In a basket-support, the combination of a casing provided with a supporting wheeled frame, a spring mounted in the casing, a framework depending upon the spring provided with oppositely-disposed basket-supporting terminal hooks, and a downwardly-extending locking-latch attached to the casing substantially as set forth.
7. In a basket-support, the combination of a casing provided with a supporting wheeled frame, a spring mounted in the casing, a framework supported by the spring provided with oppositely-disposed basket-supporting terminal hooks, and a downwardly-extending locking-latch, with a supplemental basket-supporting hook attached to the casing, substantially as set forth.
8. A basket-carrier consisting of a tubular shell provided with oppositely-located slots for a portion of its length, a trolley-bracket connected with the upper portion of the shell provided with centrally-arranged trolley-wheels, a framework of rods extending through the casing, resting upon the spring, the rods being crossed below the casing to provide a handle and oppositely-located basket-supporting hooks, a bottom plug-support for the spring, and a spring-latch depending downwardly therefrom and provided with a hook adapted to engage the handle, substantially as set forth.
9. A basket-carrier consisting of a tubular shell provided with oppositely-located slots for a portion of its length, a trolley-bracket connected with the upper portion of the shell provided with centrally-arranged trolley-wheels, a framework of rods extending through the casing, resting upon the spring, the rods being crossed below the casing to provide a handle and oppositely-located basket-supporting hooks, a bottom support for the spring, a spring-latch depending downwardly therefrom and provided with a hook adapted to engage the handle, and laterally-disposed guiding devices on the casing engaging the vertically-traveling frame, substantially as set forth.

In testimony whereof I affix my signature in presence of two witnesses.

WILLIAM E. NIECE.
